UNITED STATES PATENT OFFICE.

GARRETT W. WOODWARD, OF CHICAGO, ILLINOIS, ASSIGNOR TO J. HERBERT BENJAMIN,
OF CHICAGO, ILLINOIS.

SELF-OPERATING TALKING-MACHINE.

1,306,241.

Specification of Letters Patent. Patented June 10, 1919.

Application filed April 26, 1918. Serial No. 230,858.

To all whom it may concern:

Be it known that I, GARRETT W. WOODWARD, a citizen of the United States, residing at Chicago, in the county of Cook and State 5 of Illinois, have invented a new and useful Improvement in Self-Operating Talking-Machines, of which the following is a specification.

My invention relates to improvements in 10 talking machines of the type wherein provision is made for automatically playing in succession a plurality of records without requiring any action on the part of the operator; and my primary objects are to provide 15 improvements in machines of this type to the end that the mechanism may be simplified and rendered less expensive; that the space occupied by the mechanism and records may be reduced to the minimum, par- 20 ticularly with a view to providing a machine of such size that it will be especially desirable for household use; and to provide for the re-playing of any record, and by a simple manipulation, so condition the ma- 25 chine that it may be played in the usual way; and other objects as will be understood from the following description.

Referring to the accompanying drawings, Figure 1 is a view in side elevation, with 30 certain parts broken away, of a cabinet talking machine constructed in accordance with my invention, the parts illustrated being shown in the positions they assume while playing one of the records. Fig. 2 is an 35 enlarged elevational view of the operating mechanism shown in Fig. 1, certain parts being broken away and viewing the record-feeding devices at the irregular line 2—2 on Fig. 4. Fig. 3 is a section taken at the line 40 3—3 on Fig. 2 and viewed in the direction of the arrows. Fig. 4 is a plan section taken at the line 4—4 on Fig. 2 and viewed in the direction of the arrows. Fig. 5 is an enlarged broken view taken at the line 5—5 on Fig. 4 and viewed in the direction of the 45 arrows. Fig. 6 is a diagrammatic view of one of the similar record-feeding disks, showing a single record thereon, this view illustrating one of the intermediate positions 50 of the feeding disks. Fig. 7 is a plan view of the disk of Fig. 6. Fig. 8 is a view in elevation, partly sectional, of the feeding-disk of Figs. 6 and 7, together with its sup- 55 porting and operating mechanism, the disk being shown in the position it assumes when

in record-feeding position, a portion of a record being shown by dotted lines, in a position preparatory to feeding, and by full lines in the act of dropping from the feeding means to the turn-table of the talking machine mechanism. Fig. 9 is a view in side elevation of the lower end of the upper section of the spindle supporting and driving the record-feed disk. Fig. 10 is a similar view of the upper end of the other 60 section of this spindle. Fig. 11 is a view in side elevation of a portion of the mechanism for raising and lowering the tone-arm and swinging it out of the path of movement of the records in the feeding of the same to the 65 turn-table. Fig. 12 is a section taken at the line 12—12 on Fig. 11 and viewed in the direction of the arrows. Fig. 13 is a view in elevation of a cam-device forming a part of the mechanism of Figs. 11 and 12; and Fig. 75 14, a modification of the intermittent driving mechanism of Fig. 4.

In the particular construction shown, 15 represents a cabinet of the general shape and proportions, as commonly provided for 80 housing the mechanism of the usual non-automatic talking machine, this cabinet housing a concealed horn 16, the restricted end of which extends upwardly at the back portion of the cabinet where it terminates in 85 a socket-section 17 supported on a bracket 18 connected with the cabinet 15, this socket forming a pivotal support for a tone-arm 19, which carries a flange 20 depending against the upper edge of the socket-member 17. 90 The tone-arm 19 carries the reproducer 21, which may be of any suitable construction, such as is commonly employed in the art, the reproducer communicating with a hollow section 22 carried thereby and terminating 95 in a segmental ball-portion 23 pivoted in the outer socketed extremity 24 of the tone-arm 19, as represented at 25 to adapt the reproducer to be swung up and down on its pivot, as hereinafter described.

The cabinet 15 contains in its upper portion, which is equipped with the hinged top 26, a vertically movable frame carrying the record driving mechanism, which may be of any suitable construction. In the drawings, 105 and as I would prefer to manufacture my improved machine, the driving power is an electric motor 27 controlled through a switch button 27^a on the cabinet, this motor being supported in the frame 26 and driving a 110

shaft 28 having a governor 29, this shaft being in the form of a worm, not shown, meshing with a worm-wheel 30 fixed on the upright shaft 31 journaled in the frame 26 5 and equipped at its upper end, which is preferably socketed, as indicated at 32, with the circular turn-table or platform 33 for receiving the records to be played and which are represented at 34, it being understood 10 that when the motor 27 is operated, it will revolve the turn-table 33 in clockwise direction in Fig. 4.

The frame 26 is supported through the medium of a stem 35 connected with this 15 frame centrally thereof and provided in the form of a spiral 36, the underside of the thread thereof presenting abrupt shoulders, as represented at 37 for co-operation with pawl-mechanism which, as shown, comprises 20 a pair of pawls 38 mounted in a circular boss 39 depending from the underside of a gear 40 having journal support on the frame 43. These pawls, which are diametrically opposed, slide in channels 41 in the boss 39 25 and are backed up by a circular spring-device 42, which yieldingly holds these pawls in interlocking relation to the spiral on the stem 35. The boss 39 rests upon the upper surface of a stationary cross piece 43 30 rigidly secured to the inside of the cabinet 15, the lower end of this boss being of reduced diameter at the portion 44, at which portion it extends through an opening in the cross piece 43 and has secured thereto, 35 below this cross piece, a collar 45 to prevent upward displacement of the boss 39. The construction of this part of the mechanism is such, as will be understood, that in the rotation of the gear 40 in counter-clockwise 40 direction in Fig. 4, the stem 35 and record-driving parts carried thereby, will be caused to bodily descend, and if the operator wishes to bodily lift the mechanism just referred to, this may be done by drawing up on the 45 frame 26, the spiral 36 running idly across the ends of the pawls 38.

In accordance with the preferred illustrated embodiment of my invention, I provide the records to be automatically played, 50 in a pile or stack, and at the conclusion of the playing of any one record, automatically move the tone-arm out of the path through which the records move in the changing operation and cause, by a movement in a 55 substantially vertical plane, another record to be presented for playing, it being preferred that the records be fed one at a time from a stack thereof located in spaced relation above the turn-table 33, to a position on 60 the turn-table, on which the records pile up in superposed position as the successive playing of the same progresses, a description of the mechanism for feeding the records one by one to the turn-table being as follows:

65 Grouped about the spindle 31 preferably

equi-distantly spaced apart, to extend vertically, are spindles 46, each formed of a lower section 47 and an upper section 48. The lower spindle-sections are journaled at their upper and lower ends in bearings 49 and 50 70 stationarily mounted in the cabinet 15, and each of the sections 47 is provided at its lower end with a gear 51 rigidly connected therewith and meshing with the gear 40, the gears 51 being grouped about the gear 40 as 75 shown in Fig. 4. The upper ends of the spindle-sections 47 contain sockets, as indicated at 52, the upper walls of these sockets being recessed, as indicated at 53, to receive depending lugs 54 provided on the lower 80 ends of the spindle-sections 48, the extremities of which, represented at 55, are of reduced diameter and fit into the recesses 53, the purpose of this construction being to provide for the disengagement of the 85 spindle-sections 48 from the sections 47 and the interlocking of these sections together to permit the sections 48 to be driven from the sections 47, as hereinafter explained. Each of the spindle-sections 48 is equipped 90 at its upper end with a disk 56 rotatable therewith and containing a groove 57 in its periphery, this groove being of a thickness slightly greater than that of the record to be used on the machine. The upper flange 95 58 of the disk 56 tapers toward its outer peripheral edge, as represented in the drawings, and is cut away to the depth of the groove 57, as represented at 59. The lower flange of this disk, represented at 60, is cut 100 away to the depth of the groove 57, as indicated at 61, the purpose of these cut away portions in combination with the groove 57, being that of effecting, by the rotation of the disks 56, the separation of the lowermost record supported by these disks, from the stack of records above it to permit this lowermost record to descend into a position 105 to be played, and hold the remaining records of the stack or pile in supported position. 110 To this end the disks 56 are so arranged, as shown, that in the normal position of the parts of the machine, the lowermost record of the stack or pile thereof supported by these disks extends at its edges, into the 115 grooves 57 of the disks 56, the upper and lower flanges 58 and 60 of these disks embracing the record, as shown in Fig. 2. In the rotation of these disks in clockwise direction, the cut away portions 61 of these disks are moved into registration with the edges of this lowermost record while the flange 58 is interposed between the latter and the next record above it, with the result of permitting this lowermost record to 120 fall, as shown in Fig. 8, to become superposed on the record or pile thereof, previously placed upon the turn-table, the record running down a rod 62, which screws into the socket 32 in the center of the platform 130

33 and passes upwardly through the central holes universally provided in talking machine records. Continued rotation of the disks 56 in clockwise direction carries the 5 cut away portions 59 thereof into registration with the edges of the lowermost record of the stack, whereupon the stack of records lowers to a point where they are supported by the lower flange 60, as represented in Fig. 10 6, and further movement of the disks 56 in the same direction carries the flanges 58 into a position wherein they extend between the lowermost record of the stack and the one next above it, as represented in Fig. 2, it 15 being understood that this operation of separating the lowermost record from the stack discharging it to the turn-table and repositioning another record of the stack for delivery to the turn-table upon the next 20 operation of the feeding-mechanism, is accomplished during the turning of each disk 56 throughout one revolution.

Reference has been made to the vertically movable frame 26 carrying the turn-table 25 and driving mechanism therefor, this feature of the machine permitting of the lowering of the turn-table, each time a record is delivered to it from the feeding-mechanism referred to, a distance substantially equal 30 to the thickness of a record, so that the reproducer 21 will always be located in substantially the same horizontal plane while playing a record, regardless of the number of records superposed on the turn-table. 35 The connection, as it will be noted, between the spindles 46 and gear 40, through the medium of the gears 51, serves to cause the gear 40, each time the feed disks are rotated for the purpose hereinbefore explained, to 40 revolve sufficiently to permit the frame 26 to lower a distance equal to the thickness of a record.

As the spindles 46 are connected together through the medium of the gears 40 and 51 45 to operate in unison, it is necessary only that the driving power be applied to one of the spindles and to this end I provide on one of the spindle-sections 47, a relatively long pinion 63 carrying a bevel-gear 64, this pinion 50 being connected with the spindle-section 47, for driving the latter, by means of a pin 65 carried on one end of a spring-arm 66 secured to the pinion 63, and extending into and interlocking with a slot 67 in the spindle-section 47 (Fig. 8). The elongated pinion 63 is driven from the shaft 31 through the "medium" of intermittently-operating mechanism, a description of the form of this mechanism shown, being as follows:

60 Journaled on the frame-member 26 is a gear 68 meshing with the elongated pinion 63 and movable up and down on the latter, this gear being rigidly connected with the star-wheel 69 forming a Geneva stop, the intersecting channels 70 in which coöperate

with a pin 71 carried by a gear 72 arranged eccentric of the axis of this gear. The gear 72 meshes with a pinion 73 rigid on a gear 74 which, in turn, meshes with a pinion 75 on the shaft 31. The gear 74 and pinion 73 70 are supported at the slotted portion 76 of an arm 77 pivoted about the shaft 31, this arm having two extensions 78 and 79, the extension 79 having journaled thereon, a gear 80 which meshes with the pinion 75. 75 Means hereinafter described, are provided for shifting the arm 77 to cause the gear 72 to be driven directly from a friction roller 80^a on the gear 80, or through the train of gears 74 and 73 as desired, for a purpose 80 hereinafter explained.

It will be noted from the foregoing that power for rotating the pinion 63 and consequently the record-feeding devices, is applied intermittently only, namely, during 85 the rotation of the Geneva stop 69 by engagement with the pin 71. Inasmuch as the record-feeding devices are not to be operated to shift the records until the record previously positioned for playing, has been 90 played to the end, the gears should be so proportioned that this result will be accomplished. With the ordinary ten inch record, as now commonly provided, it is preferred that the ratio of these gears be such that 95 the record-feeding devices will be operated each time the platform revolves substantially 300 times, when the lever 77 is set to cause the drive from the shaft 31 to be through the medium of the gears 75, 74, 73, 100 and 72.

Coöperating with the swinging tone-arm 19 is a mechanism for automatically lifting the reproducer 21 from the record at the conclusion of the playing of the latter, 105 swinging the tone-arm with the reproducer to a position in which it is out of the path of movement of the descending record, and after a new record has been positioned on the revolving platform, swinging the tone-arm to cause the reproducer to extend over the record and thereupon lowering the reproducer into playing engagement with the record, a description of these means, as I prefer to construct them, being as follows: 110

Pivoted to the lower end of the tone-arm on a shaft 81 is a rock-lever 82 which extends at one end into the tone-arm where it is connected with a flexible medium, as for example a wire 83, which slides against the elbow-portion of the tone-arm and is connected at its upper end, at 84, with the inner end of the member 22, whereby when the lever 82 is rocked in clockwise direction in Fig. 2, the reproducer 21 will be lifted free 115 of the record beneath it. The outer end of the lever 82, which works through a slot 85 in the socket 17, this slot being elongated in both directions, extends across the top of a vertically-movable member, or frame, 86 120 125 130

mounted on stationary guides 87 with which it telescopes, this frame coöperating with a cam 88, on a shaft 88^a journaled in a stationary bearing 88^b, this cam being circular except for the flat portion represented at 89. The relation of these parts is such that in the rotation of the cam 88, as hereinafter described, the frame 86 will be raised from the normal position shown in Fig. 11 to a position in which the lever 82 is moved to a position in which the reproducer 21 is raised out of engagement with the record. The cam 88 carries an eccentrically-disposed pin 90 which extends into an elongated slot 91 in an uprightly-disposed lever 92 pivoted, as indicated at 93 to the part of a bracket 94 carrying the rods 87. The upper end of the lever 92, which is thus free to rock on its pivot 93 in either direction in Fig. 11, is in the form of a cross-bar 95 on which tappets 96 are mounted to be adjustable along this bar, these tappets being of such height that they will extend into over-lapping position relative to the outer end of the lever 82, when the frame 86 is in either the lower, normal, position of Fig. 11, or in the raised position hereinbefore referred to.

The cam 88 is driven through the medium of a bevel pinion 97 meshing with a bevel pinion 97^a rigid with the cam 88, the bevel-gear 97 being rigid on an inclined shaft 98 journaled at its opposite ends in bearings 99 and 100 on a stationary part of the machine. The shaft 98 has journaled thereon, a bevel pinion 101, which meshes with the bevel pinion 64, releasable means for clutching the gear 101 to the shaft 98 being provided whereby the frame 86 and rock-lever 92 are actuated from the bevel-gear 64. These releasable means comprise a spring-finger 102 connected at one end with a sleeve 103 on the gear 101 and carrying a pin 104 at its free end, which enters and interlocks with a slot 105 in the shaft 98.

A description of the operation of the machine in so far as it has been described, is as follows:

Assuming that a pile of records 34 is supported on the feed-disks 56 and the needle of the reproducer-portion 22 of the sound-reproducing mechanism is traveling in the spiral groove of a record being driven by the turn-table 33, as the needle nears the end of the record being played, the pin 71 engages the Geneva stop which rotates the latter and through the gear 68, the pinion 63 (Fig. 6) with the result of rotating the one of the feed-disks 56 connected therewith and through the medium of the gears 51 and central gear 40, rotating the other two feed-disks 56, which are thus caused to simultaneously rotate in the same direction. Concurrently with the rotation of these disks, the gear-connection 64 and 101 between the spindle 46 and the shaft 98, drives the latter and

through its gear-connection 97 and 97^a with the shaft 88^a, the cam 88 is rotated with the result of lifting the frame 86 and rocking the lever 92 to the right in Fig. 11. Thus lifting the frame 86 rocks the lever 82 in clockwise direction in Figs. 2 and 12 and tilts the reproducer portion 21 upwardly, lifting it clear of the record. The left-hand tappet 96 in Fig. 11 under the rocking action of the lever 92 moves to the right in this figure against the lever 82 with the result of swinging the tone-arm bodily in a horizontal plane on its pivot 17 while the reproducer 21 is maintained in raised position above the record, to a position in which it extends laterally beyond the turn-table 33 and thus is out of the vertical plane occupied by the records. During this actuation of the tone-arm, as stated, the disks 56 have been revolving at their unmutilated lower flange 85 portions 60 against the lowermost record supported thereby, but following the swinging of the tone-arm as stated, the mutilated portions 61 of these flanges come into registration with the edges of the lowermost 90 record and the latter thereupon slides down the stem 62 to superposed position on the previously-played record on the turn-table 33. In this discharging operation, the unmutilated portions of the top flanges 58 engage 95 the record next to be discharged (Fig. 8) and thus support the remaining records of the pile. As the feed-disks 56 continue to revolve, the mutilated portions 59 of the top flanges 58 register with the edges of the 100 records and the entire pile descends and rests on the lower flanges 60, and before these disks finish their single revolution, the upper flanges 58 move into position between the two lowermost records (Fig. 2) the normal position of the parts. The parts are so constructed and arranged that closely following the record-feeding operation, the sound-reproducer is swung back over the newly-positioned record and lowered into 110 engagement with the outer end of its record-groove, whereupon the selection presented by this record is played, the repositioning of the reproducer as just stated being effected by the swinging of the lever 92 to the left in Fig. 11, which swings the tone-arm horizontally to a position in which its reproducer is above the record, and the lowering of the frame 86 when the cam-portion 89 reaches its uppermost position which permits the 115 lever 82 to swing back to normal position in which the reproducer engages the record. The rotation of the gear 40 simultaneously with the rotation of the gears 51, causes the pawl-devices 42 to rotate therewith in clockwise direction in Fig. 3 with the result of permitting the frame 26 and parts carried thereby, to lower, these parts being so constructed and proportioned that this frame together with the turn-table 33 and other 120 125 130

parts carried thereby, will lower with each record-feeding operation a distance substantially equal to the thickness of a record. Thus the plane in which the records are 5 played remains substantially a constant.

It will be understood that in the repositioning of records for automatic feeding and in restoring the machine for normal, non-automatic, playing, the operator may readily 10 bodily lift the frame 26 and attendant parts, the pawls 38 running idly over the threads of the screw 36. It will furthermore be noted that in the raising and lowering of 15 the frame 26, the gear 68 slides lengthwise of the pinion 63 while maintaining engagement therewith.

The normal position of the lever 77 is that shown in Fig. 4 wherein the drive of the gear 20 72 is through the gears 75, 74, and 73, these gears being so proportioned that the necessary time is given for performing the operations hereinbefore explained at the conclusion 25 of the playing of a record. It may become desirable, however, as for example, in repositioning the tone-arm for replaying a record without change, to speed up the gear 72 and I have provided for this by the pivoting of the lever 77 as stated and the provision of the gear 80 and roller 80^a in addition 30 to the gears 73 and 74. The lever may connect with a spring 106 which holds it in the position shown in Fig. 4 and it may be equipped with any suitable operating mechanism, as for example the shiftable element 35 107 pivoted to the lever 77 at 108 and having a hand-piece 109 with two notches 110 and 111 coöperating with a spring detent 112 on a stationary part of the machine. When the hand-piece 109 is in the position shown 40 in the drawing, the gears 75, 74, 73, and 72 mesh, and when pulled outwardly to engage the detent 112 at the notch 110, the drive is from gear 75, through gear 80, and roller 80^a to gear 72.

45 The button 109 may, together with other buttons represented at 113 and 114, be located at any desirable and convenient place on the machine, as for example as shown in Fig. 1, the buttons 113 and 114 coöperating 50 with elements, as explained of the button 109, for controlling the lengthwise movement of blocks 115 and 116 slidable on the spindle 47 and shaft 98, respectively, for coöperation with the spring devices 65 and 55 104, to clutch and unclutch the pinion-sleeve 63 to the spindle 47, and the gear 101 to the shaft 98.

It will be understood that when the button 60 is moved to unclutch the pinion 63 from the spindle 47, no movement of the feed-disks 56 occurs when the pinion 63 is operated, but the tone-arm and reproducer are actuated as hereinbefore described with the result of repositioning the reproducer at the beginning 65 of the record played by the previous opera-

tion. Thus under the control of the operator, any one of the records may be automatically played as many times in succession as desired, and if during this repositioning of the reproducer it is desired to speed up this operation, this may be done through the button 109 to drive the gear 72 through the gear 80 and roller 80^a.

The tappets 96 should be adjusted to such positions on the cross-bar 95 as not only to 75 swing the tone-arm clear of the record prior to the record-changing operation, but to cause the stylus of the reproducer to extend above the beginning of the groove of the record to be played in the return of the reproducer to playing position, the adjustment feature of these tappets permitting of the proper automatic positioning of the reproducer for records of different diameters. The slotted-arm construction (77) of Fig. 4 80 is also provided to adapt the machine to the use of records of different diameters. Where records of different diameters, involving a greater length of spiral indented groove for coöperation with the stylus, are 85 used, the gear 74 should be larger and would be substituted for that shown, the slot 76 permitting of the adjustment of such larger gear relative to the pinion 75 to insure the 90 proper mesh.

95 In the machine shown, provision is made for automatically stopping the machine after a predetermined number of records have been played, this being accomplished by a switch shown in Fig. 2 and interposed in the 100 circuit for driving the motor 27. The switch shown is formed of a pair of contacts 117 and 118 on a block 119, the contact 118 being a spring-contact normally closing the motor-circuit through the contact 117. The 105 block is mounted on the lower end of a tube 120 supported at 121 to be vertically adjustable on the stationary frame 48 and vertically movable in this tube is a rod 122 which extends at its lower end against 110 the spring-contact 118 and at its upper end is in the path of downward movement of the top plate 123 of the frame 26. When the frame 26 lowers to a point where it bears down on the rod 122, it breaks the motor-circuit and the machine stops. By adjusting the tube 120 vertically on the frame, the machine may be set to play any desired number 115 of the records charged into the machine, a scale on the tube permitting the operator to readily position the tube to provide for the playing of the desired number of records.

When it is desired that the machine be used as in the case of the usual machine, in other words, played by the manual application of the records to the turn-table and the manual manipulation of the tone-arm and reproducer 21, the operator lifts the spindle-sections 48 from the sections 47 and by operating the buttons 113 and 114, disconnects 120 125 130

the pinion 63 from the spindles 46 and the shaft 98.

If desired, any other type of intermittent drive for the pinion 63 may be provided. 5 Such another form is that shown in Fig. 14 wherein this pinion is driven from a mutilated gear 200 geared in any suitable manner, to be constantly driven, to the gear 75, to cause the pinion 63 to operate in the desired 10 timed relation to the gear 75.

While I have illustrated and described a particular construction embodying my invention, I do not wish to be understood as intending to limit it thereto as the same may 15 be variously modified and altered without departing from the spirit of my invention, it being my intention to claim my invention as fully and completely as the prior state of the art will permit.

20 What I claim as new and desire to secure by Letters Patent is—

1. In a talking machine, the combination of a rotatable record-support, means for rotating said support, sound-reproducing 25 mechanism involving a horizontally swinging hollow tone-arm and a reproducer portion connected therewith and movable thereon toward and away from the record-support, means, extending into the interior of 30 said tone-arm and connected with said reproducer-portion, operating automatically, to first lift said reproducer from the record on said support, and thereafter swing said tone-arm out of a position immediately 35 above said support comprising a lever pivoted on said tone-arm and arranged to serve as a means of turning said tone-arm with a connection from said lever to said reproducer whereby when said lever is 40 rocked said reproducer is rocked on said tone-arm, and means for rocking said lever and thereafter bodily swinging it to first rock said reproducer out of engagement with the record and thereafter swing said 45 tone-arm to one side.

2. In a talking machine, the combination of a rotatable record-support, means for rotating said support, sound-reproducing mechanism involving a horizontally swinging tone-arm and a reproducer portion connected therewith and movable thereon toward and away from the record-support, and means, operating automatically, to first lift said reproducer from the record on said 50 support, and thereafter swing said tone-arm out of a position immediately above said support comprising a lever pivoted on said tone-arm and arranged to serve as a means of turning said tone-arm with a connection from said lever to said reproducer whereby when said lever is rocked said reproducer is rocked on said tone-arm, means for rocking said lever and thereafter bodily swinging it to first rock said reproducer 55 out of engagement with the record and 60

thereafter swing said tone-arm to one side comprising a member shiftable in one direction and engageable by said lever for rocking said lever, a second member movable in a direction cross-wise of the direction 70 of movement of said first-named member and engageable by said lever for bodily moving the latter and means for actuating said members.

3. In a talking machine, the combination 75 of a rotatable record-support, means for rotating said support, sound-reproducing mechanism involving a horizontally swinging tone-arm and a reproducer portion connected therewith and movable thereon toward and away from the record-support, means, operating automatically, to first lift said reproducer from the record on said support, and thereafter swing said tone-arm out of a position immediately above 80 said support comprising a lever pivoted on said tone-arm and arranged to serve as a means of turning said tone-arm with a connection from said lever to said reproducer whereby when said lever is rocked said reproducer is rocked on said tone-arm, means for rocking said lever and thereafter bodily swinging it to first rock said reproducer out of engagement with the record and thereafter swing said tone-arm to one side comprising 85 a member shiftable in one direction and engageable by said lever for rocking said lever, a second member movable in a direction cross-wise of the direction 90 of movement of said first-named member and engageable by said lever for bodily moving the latter and means for actuating said members.

4. In a talking machine, the combination 95 of a rotatable record-support, means for rotating said support, sound-reproducing mechanism involving a horizontally swinging tone-arm and a reproducer portion connected therewith and movable thereon toward and away from the record-support, 100 means, operating automatically, to first lift said reproducer from the record on said support, and thereafter swing said tone-arm out of a position immediately above said support comprising a lever pivoted on said 105 tone-arm and arranged to serve as a means of turning said tone-arm with a connection from said lever to said reproducer whereby when said lever is rocked said reproducer is rocked on said tone-arm, means for rocking said lever and thereafter bodily swinging it to first rock said reproducer out of engagement with the record and thereafter swing said tone-arm to one side comprising 110 a reciprocal member engaged by said 115 lever for rocking said lever, a rock member engageable by said lever for bodily moving the latter, and means for actuating said members.

5. In a talking machine, the combination 120

- of a rotatable record-support, means for rotating said support, sound-reproducing mechanism involving a horizontally swinging hollow tone-arm and a reproducer portion connected therewith and movable thereon toward and away from the record-support, means extending into the interior of said tone-arm and connected with said reproducer-portion, operating automatically, to first lift said reproducer-portion from the record on said support, and thereafter swing said tone-arm out of a position immediately above said support comprising a lever pivoted on said tone-arm and extending into the interior of the latter and arranged to serve as a means of turning said tone-arm, with a connection in said tone-arm from said lever to said reproducer-portion, whereby when said lever is rocked said reproducer-portion is rocked on said tone-arm, and means for rocking said lever and thereafter bodily swinging it to first rock said reproducer-section out of engagement with the record and thereafter swing said tone-arm to one side.

6. In a talking machine, the combination of a rotatable record-support, means for rotating said support, sound-reproducing mechanism involving a horizontally swinging hollow tone-arm and a reproducer-portion connected therewith and movable thereon toward and away from the record-support, and means extending into the interior of said tone-arm and connected with said reproducer-portion, operating automatically, to first lift said reproducer-portion from the record on said support, and thereafter swing said tone-arm out of a position immediately above said support comprising a lever pivoted on said tone-arm and extending into the interior of the latter and arranged to serve as a means of turning said tone-arm, a flexible element connected with said lever and with said reproducer-portion, whereby when said lever is rocked said reproducer-portion is rocked on said tone-arm, and means for rocking said lever and thereafter bodily swinging it to first rock said reproducer-portion out of engagement with the record and thereafter swing said tone-arm to one side.

7. In a talking machine, the combination of a rotatable record-support, means for rotating said support, sound-reproducing mechanism involving a horizontally swinging tone-arm and a reproducer portion connected therewith and movable thereon toward and away from the record-support, and means, operating automatically, to first lift said reproducer from the record on said support, and thereafter swing said tone-arm out of a position immediately above said support comprising a lever pivoted on said tone-arm and arranged to serve as a means of turning said tone-arm with a connection from said lever to said reproducer whereby when said lever is rocked said reproducer is lifted from the record on said support, and thereafter swing said tone-arm to one side.

8. In a talking machine, the combination of a rotatable record-support, means for rotating said support, sound-reproducing mechanism involving a horizontally swinging tone-arm and a reproducer portion connected therewith and movable thereon toward and away from the record-support, and means, operating automatically, to first lift said reproducer from the record on said support, and thereafter swing said tone-arm to one side comprising a lever pivoted on said tone-arm and arranged to serve as a means of turning said tone-arm with a connection from said lever to said reproducer whereby when said lever is rocked said reproducer is lifted from the record on said support, and thereafter swing said tone-arm to one side comprising a member shiftable in one direction and engageable by said lever for rocking said lever, a second member movable in a direction crosswise of the direction of movement of said first-named member and engageable by said lever for bodily moving the latter and means for actuating said members, said second member being formed of adjustable parts whereby the extent of bodily movement of the lever may be regulated.

9. In a talking machine, the combination of a rotatable record-support, means for rotating said support, sound-reproducing mechanism involving a horizontally swinging tone-arm and a reproducer portion connected therewith and movable thereon toward and away from the record-support, and means, operating automatically, to first lift said reproducer from the record on said support, and thereafter swing said tone-arm to one side comprising a member shiftable in one direction and engageable by said lever for rocking said lever, a second member movable in a direction crosswise of the direction of movement of said first-named member and engageable by said lever for bodily moving the latter and means for actuating said members, said second member being provided with tappets adjustable thereon for controlling the bodily movement of said lever.

10. In a talking machine, the combination of a rotatable record-support, means for rotating said support, sound-reproducing mechanism involving a horizontally swinging tone-arm and a reproducer portion connected therewith and movable thereon toward and away from the record-support, and means, operating automatically, to first lift said reproducer from the record on said support, and thereafter swing said tone-arm to one side comprising a lever pivoted on said tone-arm and arranged to serve as a means of turning said tone-arm with a connection from said lever to said reproducer whereby when said lever is rocked said reproducer is lifted from the record on said support, and thereafter swing said tone-arm to one side comprising a member shiftable in one direction and engageable by said lever for rocking said lever, a second member movable in a direction crosswise of the direction of movement of said first-named member and engageable by said lever for bodily moving the latter and means for actuating said members, said second member being formed of adjustable parts whereby the extent of bodily movement of the lever may be regulated.

rocking said lever and thereafter bodily swinging it to first rock said reproducer out of engagement with the record and thereafter swing said tone-arm to one side comprising a reciprocable member engaged by said lever for rocking the latter, a rock member located adjacent said reciprocable member and provided with projections for engaging said lever to bodily move the latter, and means for actuating said members.

10. In a talking machine, the combination of a rotatable record-support, means for rotating said support, sound-reproducing mechanism involving a horizontally swinging tone-arm and a reproducer portion connected therewith and movable thereon toward and away from the record-support, and means, operating automatically, to first lift said reproducer from the record on said support, and thereafter swing said tone-arm

out of a position immediately above said support comprising a lever pivoted on said tone-arm and arranged to serve as a means of turning said tone-arm with a connection from said lever to said reproducer whereby 25 when said lever is rocked said reproducer is rocked on said tone-arm, and means for rocking said lever and thereafter bodily swinging it to first rock said reproducer out of engagement with the record and thereafter swing said tone-arm to one side comprising a reciprocable member engaged by said lever for rocking the latter, a cam device for reciprocating said member, a rock member provided with projections and 35 adapted to engage said lever for bodily moving the latter, and means for rocking said rock member.

GARRETT W. WOODWARD.
